Howard A. Kehl, Detroit, Mich.

Application October 22, 1958, Serial No. 53,097

Term of patent 14 years

(Cl. D87—3)

FIG. 1.

FIG. 2.

FIG. 3.

FIG. 4.

FIG. 5.

FIG. 6.

FIG. 7.

Figure 1 is a front elevational view of a slip-on belt billfold shown in flexed wearing position, and showing my new design.

Figure 2 is a rear elevational view thereof.

Figure 3 is a top plan view of same.

Figure 4 is a cross-sectional view of Fig. 1 taken on line 4—4 of Fig. 1.

Figure 5 is a front elevational view of same on a reduced scale, showing the slip-on belt billfold in unflexed, non-wearing position.

Figure 6 is a rear elevational view of same on a reduced scale, showing the slip-on belt billfold in unflexed, non-wearing position.

Figure 7 is a front elevational view of same shown in

flexed wearing position also on a reduced scale, and showing a portion thereof broken away to show an inside pocket.

I claim:

The ornamental design for a slip-on belt billfold, as shown and described.
